CONTROL SYSTEM

Paul S. Dickey, Cleveland, Ohio, assignor to Bailey
Meter Company, a corporation of Delaware

Application July 14, 1936, Serial No. 90,615

32 Claims. (Cl. 122—407)

This invention relates to methods of and apparatus for operating vapor generators; particularly vapor generators of the drumless, forced flow type, having a fluid flow path including one or more long small-bore tubes, in which the flow in the path is initiated by the entrance of liquid under pressure at one end, and the exit of vapor only at the other end; characterized by an inflow of liquid normally greater than the outflow of vapor, the difference being diverted from the path intermediate the ends thereof.

Such a vapor generator, having small liquid storage and operated with wide range combustion devices, forms a combination rendering practical extremely high heat release rates with the consequent ability to economically handle practically instantaneous load changes from minimum to maximum, and vice versa, without heavy standby expense, and is particularly suitable for operating conditions such as locomotive service, where load variations are of a wide range and are required to be met substantially instantaneously.

The generator has a minimum liquid storage capacity with a maximum heat absorbing surface so disposed and arranged as to be substantially instantaneously responsive to rapid changes and wide diversities in heat release rate in the furnace. The heat absorbing surface is arranged in relation to the path of the products of combustion and radiant heating so that the entering liquid is received at the cooler end of the path. Further, the vapor generator insofar as the passage of combustion gases is concerned has a continuously increasing resistance to gas flow throughout the length of the passage.

The heat absorbing surface, or flow path for the working medium, is preferably comprised of a plurality of long small-bore tubes with an enlargement, preferably at the end of the generating section, which acts as a separator to divide liquid and vapor. The vapor is then passed through a superheater, while the excess liquid carried through the tubes of the generating section for the purpose of wetness and preventing scale deposit, is diverted out of the separator under regulated conditions, as will be herein-after set forth. The solids carrying liquid diverted out of the flow path at the separator location is divided, with a portion sent to waste and the remainder recirculated through the generating portion of the fluid flow path. It is in the control of such diverted liquid and the recirculation thereof that I am particularly concerned in the present invention.

Through the utilization of the present invention I am enabled to recirculate a considerable percentage of the liquid entering the flow path and with advantageous results. For example, such recirculation may comprise twenty, thirty or even fifty percent of the liquid entering the flow path under pressure. So long as such recirculation can be accomplished without loss of heat and without the expenditure of considerable power there are material advantages to be gained.

In the forced circulation type of vapor generator comprising a once through fluid path of one or more long, small-bore tubes, with a very small liquid storage and a very high rate of evaporation it is known that the vaporization zone within the path is the location where substantially all of the solids carried by the liquid will be deposited or left in suspension through vaporization of liquid. If not deposited, due to the extreme agitation of the liquid, they will serve to continuously increase the concentration of solids in the liquid remaining in the tube path ahead of the vaporization zone. In the separator type of forced circulation boiler, with a material excess of liquid inflow to the path over vapor outflow from the path, the economizer and generating section prior to the separator will be at all times wetted to prevent scale formation and will be provided with sufficient liquid to wash all of the solids into the separator. Thus the separator comprises a relatively quiescent zone where separation of vapor and liquid may occur and to which substantially all of the solids of the liquid inflow are carried.

It has been known to continuously divert excess liquid from the flow path at the separator and to discharge such liquid to waste. This means a considerable constant loss of liquid and of the heat contained therein and the tendency is to reduce the excess liquid to as low a value as possible to save this loss. Preferable operation would be to have a materially greater excess of liquid flowing through the economizer and generating sections than is economically possible if all of the excess is discharged to waste from the separator drum.

Other operation has been to return for recirculation a major portion of the spillover or discharge from the separator drum and either to pass this directly to the hot well, to the economizer entrance, or to the generating section entrance, and with or without prior passage through heat exchanger apparatus. The capital

expenditure and upkeep of such heat exchanger apparatus is almost prohibitive. The recirculation of the liquid from the separator drum, regardless of the heat saving or loss of such liquid, means that the solids which have purposely been carried through into the separator for the purpose of taking them out of the tube path are now again brought into the tube path through recirculation.

Such a vapor generator has substantially no heat storage capacity either in the metal parts or in the small volume of liquid stored. It is capable, however, of very fast changes in heat release and absorption rates. However, through the advantages of my invention I have been able to materially increase the speed at which load changes may be made, through the utilization of the liquid stored in the separator drum at substantially vaporization temperature. Furthermore, I accomplish a recirculation of a very large percentage of the liquid inflow at substantially vaporizing temperature and without an increase in feed pump capacity or power requirements, and in fact under certain conditions of design I have been able to materially reduce the feed pump size, or power requirement.

In addition, the invention accomplishes the very necessary desideratum of balancing the plurality of parallel circuits insofar as resistance, flow, temperature, and heat are concerned. Through the recirculation of a very large percentage of the liquid inflow the concentrates are diluted and only a small percentage of the spill-over from the separator drum is sent to waste.

In short, I desirably recirculate a higher percentage of liquid inasmuch as no heat is lost and send to waste only a small percentage to blow down the concentrates. I introduce the recirculated liquid into the flow path entrance through the agency of injectors with approximately the same pressure drops as the previously used balancing, flow resistors, to serve as circulating pumps to increase the rate of circulation in the vaporization zone without requiring the pumping of extra water by the main feed pump nor the loss of high potential heat occasioned by means of the spillover which formerly must go to the feed water heaters or some similar point of low heat potential. With a larger percentage of inflow being recirculated instead of to drain, the main feed pump need handle less liquid and require less power.

In the multi-circuit path of a forced flow vapor generator it is usual to introduce flow restrictors or equalizers between the economizer and vapor generating sections of the path, to attempt to attain equalization of flow through the tubes of the generating section and prevent overheating of one tube as compared to another through starvation of liquid. The flow restrictors are usually sections of tubing of relatively small diameter introducing a resistance to flow of several times that of the tube path following, so that variations in flow resistance of said following tube path will be of minimized effect relative to the total resistance including the flow restrictors. Through multiplying the flow resistance several times in this manner it is, of course, necessary to overcome such resistance with feed pump power.

I propose to replace such flow restrictors by injectors inserted in the several tube portions of the path at the entrance to the vapor generating section, utilizing pressure drop therethrough to

75 pump or recirculate the liquid from the separator drum and with the knowledge that such a plurality of injectors will tend to be self-equalizing insofar as the combined effect of heat and flow distribution between the different tube sections is concerned. Any generating tube which has the tendency, due to unequal application of heat for example, to generate more steam than its parallel tubes tends to become overheated through the presence of generated steam within the tubes rather than a wetting liquid.

10 While the previous flow restrictors or balancing resistors tend to minimize the effect of inequalities in tube resistance and thereby to equalize flow in the parallel tube circuits, the substitution of an injector for each flow restrictor, with a nozzle resistance commensurate with that of a restrictor, serves not only to retain the advantage of flow equalization but additionally tends toward an equalization of heat, temperature and proportions of the vapor-liquid mixture leaving the tubes.

15 By way of example; should any particular circuit tend to become overheated due either to decrease in flow or increase in heat input (as by localized heating), the pressure drop in that circuit increases due to the increased portion occupied by steam, and this of course may progress until excessive superheating is obtained at the circuit outlet. However, the increased pressure drop of the circuit raises the delivery pressure of the injector and thus decreases its pumping capacity and the amount of recirculated water from the separator drum which enters the circuit.

20 Therefore, the temperature of the mixed feedwater and recirculated water entering this particular circuit is reduced and likewise the tendency toward excessively high ratio of steam to water, or high dry steam temperatures leaving the circuit is checked. Similarly, if a particular circuit receives insufficient heat, a smaller proportion of that circuit will be occupied by steam and the circuit resistance reduced. This results in a decrease in injector delivery pressure

25 and thus an increase in the amount of recirculated water pumped by the injector and entering that circuit. The water withdrawn from the separator drum for recirculating through the generating portion of the flow path is preferably introduced at the entrance to the generating portion where the temperature of the water coming from the economizer is materially lower than the temperature of the recirculated water. (See Fig. 6.) Thus since the net temperature of the water entering the furnace or steam generating portion of the path depends on the ratio of recirculated to feed water, it is increased and the rate of steaming is accelerated.

30 No such heat and/or temperature equalizing tendency is obtained with flow restrictors. When they alone are used, one must depend upon the total resistance, that is, resistors plus tube resistance must be near enough alike in the different circuits to tend to equalize flow therethrough. Through my invention, by the substitution of injectors for flow resistors, there is a greater tendency towards circuit equalization of flow, heat, and temperature, since I have not lost the action of high pressure drop in equalization of flows and at the same time I have gained a tendency toward equalization of fluid thermal conditions leaving the circuits by automatically regulating the feed temperature entering the circuits in an opposite sense to the amount of steam being generated in

any particular circuit. Thus the use of the injectors in place of the balancing resistors tends to automatically balance the tubes in the parallel circuit insofar as flow, heat, temperature, etc. are concerned.

The scheme consists essentially of elimination of the present balancing resistors or flow equalizers and the substitution therefor of injectors with approximately the same pressure drop which will serve as circulating pumps for the individual tube circuits to increase the rate of circulation in the vaporizing zone without requiring the pumping of extra water by the main feed pump. The pressure drop of the present balancing resistors may be used as energy through the injector action to pump at least twenty to thirty percent of the flow rate back from the separator drum to the entrance of the vaporizing section.

It does not appear necessary to go into the reasons for employing a plurality of long small bore tubes for the forced flow path, inasmuch as this is well recognized in the art. Suffice it to say that having such construction it is of prime importance that the plurality of circuits be equalized insofar as flow, heat, temperature, etc. are concerned.

In the drawings:

Figs. 1, 2, 3 and 4 are diagrams of vapor generator flow circuits.

Fig. 5 diagrammatically illustrates a drumless forced flow vapor generator to which the present invention is directed.

Fig. 6 diagrammatically illustrates the flow circuit of a vapor generator embodying the invention.

Figs. 7, 8 and 9 are typical injector constructions.

Fig. 10 diagrammatically illustrates a drumless forced flow vapor generator, combined with the requisite apparatus to control the functioning thereof, and such apparatus shown in partially diagrammatic fashion.

To more readily bring out the salient features of my invention I have illustrated in Figs. 1, 2, 3 and 4 the flow circuits of certain prior constructions as well as that of the present invention. In Fig. 1 it will be observed that four units of makeup water are forced by the pump through the economizer section, through the resistance of the flow equalizers, thence through the generating section, and into the separator. From the separator, three units of steam are passed out and one unit of liquid carrying the concentrates is passed to waste through a heat exchanger. The resistance of the flow equalizers is included in the work which the inflow pump must do. The heat exchangers, employed for the purpose of conserving the heat of the waste liquid, are expensive insofar as capital investment, repair, upkeep, etc. are concerned. Twenty-five percent of the total water pumped by the inflow pump is thrown to waste and a certain amount of heat which cannot be taken out by the heat exchangers.

In Fig. 2 all of the spillover from the separator drum is recirculated by the inflow pump and while substantially no heat is lost (through passing the spillover to waste), nevertheless the liquid within the economizer and generating section are continually gaining in concentration of solids. The pump is of the same size as in Fig. 1 and while the heat exchangers are not necessary and the heat of the spillover liquid is conserved, it is at the expense of rapidly increasing the solids

content of the liquid within the flow path and the danger of damaged tubes therefrom.

In Fig. 3 3.5 units of make-up are pumped, .5 unit is continually thrown to waste, and 1.5 units are recirculated from the entrance of the generating section. In this example a small portion of liquid is continually thrown to waste with consequent loss of the heat therein and loss of the power necessary to pump the liquid through the flow path. Furthermore, a second pump P' is required for the recirculated liquid which is introduced after the economizer section. The total pump capacity is thus greater than in the examples Figs. 1 and 2. The advantage gained by the arrangement of Fig. 3 is a larger volume of liquid passing through the generating section, thus diluting the concentration and furnishing (at the entrance to the generating section) a greater flow of nearly steaming liquid in relation to the vapor outflow from the separator drum. In other words, while three units of fluid pass from the separator as vapor, there are five units of nearly steaming liquid entering the generating section at all times.

Referring now to Fig. 4 I illustrate therein the arrangement of my invention which has material advantages over the prior arrangements of Figs. 1, 2 and 3.

In Fig. 4 I indicate a make-up of liquid of 3.25 units, a discharge to waste of .25 unit and a recirculation of 1.75 units. Through the utilization of injectors between the economizer and generating portions of the path I have made use of the otherwise wasteful pressure loss of the flow equalizers. In other words the injectors of the plurality of circuits would have substantially the same pressure drop as the previously mentioned flow equalizers but would utilize such pressure drops in actually pumping into the generating section the recirculated spillover. Thus the pump of Fig. 3 indicated at P' would be eliminated and the make-up pump would be of substantially the same size as required in Fig. 3. There is substantially no loss in heat in the large volume of recirculated spillover. This recirculated liquid at nearly vaporizing temperature is available at the inlet to the generating section at all times, and as previously brought out is fed proportionate to the rate of operation of the generator as a whole. In other words, as demand upon the generator increases, the injector action will automatically increase, thus drawing a greater volume of recirculated spillover from the separator drum, utilizing the stored liquid thereof, and at no additional pumping expense. The additional volume of highly heated liquid entering the generating section will materially speed up the load-taking-on ability of the generator as a whole. This is further amplified due to the swell of the liquid within the separator when load suddenly increases and pressure on the separator correspondingly suddenly decreases. Such swell or increased volume of liquid within the separator will afford a very welcome additional supply of highly heated liquid to the entrance of the generating section.

Additionally, as previously mentioned, the use of the injectors serves a primary and highly important function in heat and flow equalization between the plurality of circuits as compared to the fixed flow equalizers of prior constructions. Equalization between the various circuits of the generating section will be automatic at times of change in load and self-equalizing to counteract

the adverse effects of localized heating or other sources of trouble in operation. Such equalizations will be of flow, temperature, heat, etc.

Having now described in a more general manner the advantages of my invention in relation to known constructions and methods of operation, I will now describe in detail the apparatus utilized in carrying out the preferred form of the invention.

The drumless forced flow vapor generator to which the present invention is directed is diagrammatically illustrated in Fig. 5 to indicate gas flow, working fluid flow, and heat absorbing surface arranged as contained within the enclosure represented by the dot and dash lines.

The flow path for the working medium is comprised of long small-bore tubes brought together at suitable headers. The generator includes an economizer 1 at the cooler end of the gas passage and which receives liquid from a positive displacement pump which may be connected to a hot well.

The liquid from the economizer outlet header 2 is conveyed by a tube 3 to a manifold tube 4 from which the liquid is distributed to the generating section through, in this instance, five injectors 5, each of which has a certain resistance drop preferably greater than the particular fluid flow passage which it serves, and whereby the liquid is proportionately distributed to each of the tubular fluid flow passages 6, 7, 8, 9 and 10 constituting the generating section of the assembly which comprises floor, wall, screen and roof portions as indicated.

These five flow circuits comprising the vapor generating surface tangentially enter a bulge in the fluid flow path which is in the form of a separating chamber 11 for dividing the fluid into liquid and vapor, the vapor passing to a superheater 12 and the excess liquid being diverted from the fluid flow path through a pipe 13 to the injectors or to waste.

The "Heat source" (Figs. 5 and 10) includes an oil burner 14 supplied by a pipe 15 and an air chamber 16 supplied by a conduit 17. Ordinary provision for initial ignition, safety features, etc. may be provided.

In Fig. 5 the spillover pipe 13 is divided to form a controlled bleed to waste, a controlled flow to the injectors, and a fixed flow to the injectors.

In Fig. 6 I illustrate diagrammatically the flow path of the working medium without respect to the sequence of heating. I have indicated certain temperature-pressure conditions as a single example of what might be encountered under certain conditions of design and operation at different points along the flow path.

In Figs. 7, 8 and 9 I illustrate diagrammatically different forms of injectors which may be utilized in the individual flow circuits between the economizer and the vaporizing or generating zone. The particular injector forms no part of the present invention but will be designed to give desired pressure drops, flow capacities and characteristics.

Referring now in particular to Fig. 10 I illustrate the fluid flow path as a single sinuous tube, to the economizer section 1 of which liquid is supplied under pressure through a pipe 18 from a pump 19, which while it is illustrated in Fig. 5 as a positive displacement pump may be of any suitable type and which I have therefore illustrated in Fig. 10 merely diagrammatically. From the economizer section the fluid passes to and through the generating section discharging into the separator 11. From the separator vapor

passes to and through the superheater 12 to a main turbine 20 illustrative of a vapor consuming device. Products of combustion pass successively through the generating section, superheater, and economizer and may contact a part or all of the separator.

An auxiliary turbine 21 drives the liquid feed pump 19, the air blower 22, and the fuel supply pump 23. While I have illustrated these devices diagrammatically and as though all are located to be driven by the same shaft and at the same speed, it will be understood that the necessary gear reduction or driving connections between the several devices are known and would be properly designed as to relative speed, power, etc. and that I merely intend to indicate that the auxiliary turbine 21 drives the devices 19, 22 and 23 simultaneously and in unison.

The rate of supply of fuel oil to the burner 14 is primarily controlled by the speed of the oil pump 23 but the supply of oil is further regulated by the throttling of a regulating valve 24 located in the pipe 15, and the rate of flow is continuously measured by a meter 25.

The rate of supply of air to support combustion is primarily determined by the speed of the blower 22, but is further under the control of a damper 26 positioned in the conduit 17 at the inlet to the blower. The rate of supply of air is continuously measured by a flow meter 27.

The rate of supply of liquid under pressure through the conduit 18 is primarily controlled by the speed of the pump 19 but is further influenced through the positioning of a regulating valve 28 at the suction side of the pump.

29 represents means responsive to liquid level within the separator 11 and constitutes a pressure casing enclosing a mercury U-tube connected across the vertical elevation of the separator. A float is adapted to rise and fall with the surface of the mercury in one leg and to thus cause a positioning of a pointer 30 relative to an index 31 to advise the instantaneous value of liquid level and to further vertically position the stem 32 of a pilot valve 33 to establish an air loading pressure representative of liquid level. Such an air loading pressure decreasing with rise in level is transmitted through the pipe 34 to the averaging relay 35. An air loading pressure increasing with rise in level is transmitted through the pipe 36 to a diaphragm actuated valve 37.

A rate of flow meter 38 continuously indicates the rate of vapor outflow through the conduit 39 and positions a pilot stem 40 in accordance therewith. The air loading pressure representative of rate of vapor outflow is effective within a chamber of the averaging relay 35. The averaging relay 35 is connected by means of a pipe 41 with the diaphragm chamber of the valve 28 to position the same responsive to both variations in rate of vapor outflow and variations in liquid level within the separator 11. For example, liquid inflow is held roughly in proportion to vapor outflow and is readjusted to maintain desirable level within the separator. While the rate of liquid inflow is not entirely under the control of regulating valve 28, it is primarily so for the pressure drop across the valve 28 is utilized in positioning auxiliary turbine governor 42.

A Bourdon tube 43 is sensitive to vapor outflow pressure and positions an indicator 44 relative to an index 45, as well as a pilot stem 46 in a pilot valve 47. An air loading pressure is thus established representative of vapor outflow pressure effective in positioning the damper 26 as well as

a diaphragm actuated valve 48 in one spillover line from the separator 11.

The rate of flow meters 25, 27 coact to position a pilot stem 49, establishing a loading pressure effective for positioning the fuel oil valve 24. Should fuel flow-air flow depart from desired relationship the valve 24 will be positioned to readjust the flow of fuel oil and reestablish such desired relationship.

Certain features of the general arrangement in method and apparatus for operating such a vapor generator are disclosed and claimed in my copending application, Serial No. 55,023, filed in the United States Patent Office December 18, 1935, now Patent 2,170,346.

The concentration of solids in the liquid within the separator 11 is continuously determined by means of a conductivity cell 50 located near the bottom or most quiescent portion of the separator. The conductivity cell 50 is effective in positioning a regulating valve 51 located in a pipe leading to waste. The adjustment is normally such that a relatively small volume of liquid is continuously passed to waste through the valve 51 and the rate of flow is varied dependent upon variations in concentration of liquid within the separator.

A second pipe 52 leads from the separator 11 to waste or any desired location. Flow through the pipe 52 is under the control of the valve 37 and the arrangement is such that the valve 37 is to be opened only under emergency high level conditions within the separator 11. Should level within the separator reach a predetermined high level the level responsive device 29 will so position the pilot stem 32 that an air loading pressure will be established through the pipe 36 upon the valve 37 and cause the valve to open quickly and in large degree to take care of such emergency conditions until the level is brought down to below the emergency point.

A third pipe 53 leads from the separator 11 and is branched as at 54. In the pipe 53 is located the regulating valve 48 under the control of a loading pressure established representative of vapor outflow pressure. The branch 54 has a fixed resistance 55 and joins the pipe 53 again before the pipe 53 reaches the injectors 56. It is understood that the pipe 53 will be branched to each of the injectors 56 located in the individual parallel tube circuits as indicated in Fig. 5.

Under normal conditions of operation variations in vapor outflow effective upon the meter 38 will result in variations of auxiliary turbine speed to proportion liquid inflow, air and oil to the variations in load. Should level within the separator vary, such changes will also be effective in controlling auxiliary turbine speed, although the magnitude of the changes in auxiliary turbine speed for changes in level may be quite different than the magnitude of changes in auxiliary turbine speed for changes in vapor outflow rate.

The supply of air to support combustion is readjusted over changes in blower speed through the agency of the damper 26 under the control of the vapor outflow pressure sensitive device 43. Fuel oil supply is readjusted in accordance with fuel flow-air flow relation.

As indicated in Fig. 4 and previously described, a considerable portion of the liquid entering the separator 11 is recirculated to the entrance of the generating section and this may amount to twenty, thirty or even fifty percent by weight. During normal operation twenty to thirty per-

cent of the vapor outflow rate as liquid is allowed to pass through the resistance 55 and enter the injectors 56 to prevent superheating in the generating section and to balance steam quality of mixture from the various circuits entering the separator. Upon increasing load the regulating valve 48 in the branch 53 is opened responsive to an indication of load as represented by vapor outflow pressure and this serves to reduce the separator liquid level and increase the flow through the circuit in the generating section up to 1.70 to 2.0 times the output rate, thus utilizing the swell in the separator drum to make additional vapor output. Thus by materially reducing the total resistance of the spillover lines 53, 54 as much as seventy to eighty percent of flow can be recirculated through the spillover lines at times of sudden load increase when there is a surge of level within the separator drum.

Under emergency conditions should the level within the separator 11 rise to a dangerous point, the valve 37 will be opened quickly and in considerable degree to relieve the condition. A very small amount of liquid is continually passed to waste through the valve 51 under the control of a concentration or conductivity cell 50.

While I have chosen to illustrate and describe certain embodiments of my invention I am not to be limited thereto but only as to the claims in view of prior art.

What I claim as new, and desire to secure by Letters Patent of the United States, is:

1. The method of operating a vapor generator of the forced flow type having a separator between the generating and superheating portions of the flow path, which includes recirculating a material percentage of the liquid leaving the generating section, and varying the percentage recirculated responsive to load on the generator.

2. The method of operating a vapor generator of the forced flow type having a separator between the generating and superheating portions of the flow path, which includes, recirculating a material percentage of the liquid entering the separator, and utilizing the pressure drop of a portion of the path to introduce the recirculated liquid at the entrance of the generating section.

3. The method of operating a vapor generator of the forced flow type having a separator between the generating and superheating portions of the flow path, which includes, passing fluid under pressure through a plurality of parallel circuits in the generating portion, recirculating a material percentage of the liquid entering the generating circuits through said circuits, and utilizing injector action at the entrance to the individual circuits to proportion the circulation to the circuits.

4. The method of operating a vapor generator of the forced flow type having a plurality of parallel circuits in the generating portion, which includes, diverting a material percentage of the liquid from adjacent the vaporization zone of the path, reintroducing the diverted liquid to the plurality of generating circuits, continuously passing a portion of the diverted liquid, and regulating the flow of the remainder responsive to load on the generator.

5. The method of operating a vapor generator of the forced flow type having a plurality of parallel circuits in the generating portion, which includes, diverting a material percentage of the liquid from adjacent the vaporization zone of the path, reintroducing the diverted liquid to the generating circuits, allowing a portion of the di-

verted liquid to continuously pass to the circuits, and controlling the flow of the remainder of diverted liquid responsive to vapor outflow pressure.

6. In combination, a vapor generator of the forced flow type having a plurality of tube circuits in the generating portion, a separator adjacent the vaporization zone, an injector in each of said tube circuits, and means diverting liquid from said separator to the injectors.

7. In combination, a vapor generator of the forced flow type having a plurality of tube circuits in the generating portion, an injector at the entrance of each of said circuits, and means diverting liquid from adjacent the vaporization zone of the flow path and returning such liquid to the plurality of injectors.

8. The method of operating a vapor generator of the forced flow type having a generating portion, which includes, diverting a material percentage of the liquid from adjacent the vaporization zone of the path, reintroducing the diverted liquid to the generating portion, continuously passing a portion of the diverted liquid, and regulating the flow of the remainder responsive to load on the generator.

9. The method of operating a vapor generator of the forced flow type having a generating portion, which includes, diverting a material percentage of the liquid from adjacent the vaporization zone of the path, reintroducing the diverted liquid to the generating portion, allowing a portion of the diverted liquid to continuously pass to the generating section, and controlling the flow of the remainder of diverted liquid responsive to vapor outflow pressure.

10. The method of operating a vapor generator of the forced flow type having a separator between the generating and superheating portions of the flow path, which includes recirculating a material percentage of the liquid leaving the generating section, and varying the percentage recirculated responsive to vapor outflow pressure.

11. The method of operating a fluid treating system wherein a portion of the entering liquid is vaporized, which includes, passing the liquid and vapor mixture to a relatively quiescent separator section, allowing the vapors to separate and pass away, recirculating a portion of the unvaporized fluid to the entrance of the treating zone, and varying the percentage recirculated responsive to a vapor output variable.

12. The method of operating a fluid treating system wherein a portion of the entering liquid is vaporized, which includes, passing the liquid and vapor mixture to a relatively quiescent separator section, allowing the vapors to separate and pass away, recirculating a portion of the unvaporized fluid to the entrance of the treating zone, and varying the percentage recirculated responsive to vapor outflow pressure.

13. The method of operating a vapor generator of the forced flow type having a separator between the generating and superheating portions of the fluid flow path, which includes continuously recirculating a material percentage of the liquid entering the generating section, and varying the percentage recirculated responsive to a variable condition in the operation of the vapor generator.

14. The method of operating a vapor generator of the forced flow type having a plurality of parallel circuits in the generating portion, which includes, diverting a material percentage of the liquid from adjacent the vaporization zone of the path, reintroducing the diverted liquid to the

generating circuits, allowing a portion of the diverted liquid to continuously pass to the circuits, and regulating the flow of the remainder of diverted liquid responsive to a variable condition in the operation of the vapor generator.

15. The method of operating a vapor generator of the forced flow type having a generating portion, which includes, diverting a material percentage of the liquid from adjacent the vaporization zone of the path, reintroducing the diverted liquid to the generating portion, continuously passing a portion of the diverted liquid, and regulating the flow of the remainder responsive to a variable condition in the operation of the vapor generator.

16. The method of operating a vapor generator having a small liquid storage with a high rate of evaporation, which includes, continuously diverting a material percentage of the liquid fed to the generator from adjacent the vaporization zone of the generator, reintroducing such diverted liquid to the generator at another location, and controlling the percentage reintroduced responsive to a variable condition in the operation of the vapor generator.

17. The method of operating a vapor generator having a forced flow path receiving liquid under pressure at one end and delivering vapor at the other and having heating provisions, which includes, continuously diverting a material percentage of the liquid from adjacent the vaporization zone of the path, reintroducing at least a portion of the diverted liquid to the path at another zone, and regulating the percentage reintroduced responsive to a variable in the operation of the vapor generator.

18. The method of operating a fluid treating system wherein a portion of the entering liquid is vaporized, which includes, passing the liquid and vapor mixture to a relative quiescent separator section, allowing the vapors to separate and pass away, continuously recirculating a portion of the unevaporated fluid to the entrance of the treating zone, and varying the percentage recirculated responsive to a variable condition of the fluid.

19. The method of operating a vapor generator of the forced flow type having a separator between the generating and superheating portions of the flow path, which includes, recirculating a material percentage of the liquid entering the separator, and utilizing the pressure drop of a portion of the path to introduce recirculated liquid at said portion of the path.

20. In combination, a vapor generator of the forced flow type having a plurality of tube circuits in the generating portion, an injector in each of said circuits, means diverting liquid from adjacent the vaporization zone of the flow path and returning such liquid to the plurality of injectors, and means responsive to a variable condition of the fluid and adapted to regulate the amount of liquid returned.

21. In combination, a vapor generator of the forced flow type having a plurality of parallel tube circuits in the generating portion of the fluid flow path, means continuously recirculating liquid from adjacent the vaporization zone of the path to a location near the beginning of the generating portion, and other means under the control of a vapor outflow variable supplementing such recirculated liquid with liquid from the path.

22. In combination, a vapor generator of the forced flow type having a plurality of parallel

tube circuits in the generating portion of the fluid flow path, a separator in the path adjacent the vaporization zone, means continuously recirculating liquid from said separator to the generating portion responsive to a variable of the fluid, means diverting liquid from the separator responsive to a measure of concentration of the liquid, and means diverting liquid from the separator when an excessive level of liquid within the separator is reached.

23. The method of operating a vapor generator of the forced flow type having a plurality of parallel circuits in the generating portion, which includes, diverting a material percentage only of the unevaporated liquid from adjacent the vaporization zone of the path, reintroducing the diverted liquid to the plurality of generating circuits, and automatically proportioning the recirculated liquid to the generating circuits.

24. In combination, a vapor generator of the forced flow type having a plurality of tube circuits in the generating portion, an injector at the entrance of each of said circuits, and means diverting fluid from adjacent the vaporization zone of the flow path and returning such fluid to the plurality of injectors.

25. The method of operating a forced circulation fluid treating system wherein the entering fluid contains a material percentage of liquid, which includes, heating the treating zone of the forced circulation path to a degree whereby a portion of the entering liquid is vaporized, passing the liquid and gas and vapor mixture to a relatively quiescent separator section, continuously recirculating a portion of the treated fluid to the entrance of the treating zone, and varying the percentage recirculated responsive to a variable condition of the fluid.

26. The method of operating a fluid treating system wherein a portion of the entering fluid is vaporized, which includes, passing the liquid and vapor mixture to a relatively quiescent separator section, allowing the vapors to separate and pass away, supplying liquid to the system in excess over the vapor rate of discharge, and maintaining the excess proportional to the vapor rate of discharge and varying the proportion in response to a variable condition of the fluid.

27. In combination, a vapor generator of the forced flow type having a generating tube portion, a separator adjacent the vaporization zone, a pipe connecting the separator with the entrance of the generating tube portion providing a substantially fixed resistance non-regulable fluid path through which liquid returns from the separator to the entrance of the generating tube portion, a second pipe parallel to said first pipe and having therein a regulating valve, and means responsive to a vapor output variable positioning said regulating valve.

28. In combination, a vapor generator of the forced flow type having a generating tube portion, a separator adjacent the vaporization zone, a pipe connecting the separator with the entrance of the generating tube portion providing a substantially fixed resistance non-regulable fluid path through which liquid returns from the separator to the entrance of the generating tube portion, a second pipe parallel to said first pipe and having therein a regulating valve, and means responsive to vapor outflow pressure positioning said regulating valve.

29. In combination, a vapor generator of the forced flow type having a generating tube portion, a separator adjacent the vaporization zone, a pipe connecting the separator with the entrance of the generating tube portion providing a substantially fixed resistance non-regulable fluid path through which liquid returns from the separator to the entrance of the generating tube portion, a second pipe parallel to said first pipe and having therein a regulating valve, and means responsive to a variable condition of the fluid positioning said regulating valve.

30. The method of operating a vapor generator of the forced flow type having a separator between the generating and superheating portions of the flow path, which includes, recirculating a material percentage only of the liquid entering the separator, and utilizing the fluid velocity through a portion of the path prior to the separator to effect the introduction of recirculated liquid at said portion of the path.

31. The method of operating a fluid treating system wherein a portion of the entering liquid is vaporized, which includes, passing the liquid and vapor mixture to a relatively quiescent separator section, allowing the vapors to separate and pass away, recirculating a portion only of the unevaporated fluid to the entrance of the treating zone, and utilizing the fluid velocity through a portion of the path prior to the separator to effect the introduction of recirculated liquid at said portion of the path.

32. In combination, a vapor generator of the forced flow type having a generating tube portion, a separator adjacent the vaporization zone, a pipe connecting the separator with the entrance of the generating tube portion providing a path through which a portion only of the unevaporated liquid returns from the separator to the entrance of the generating tube portion, an injector type means in the path near the entrance of the generating portion and to which said pipe connects whereby the velocity effect of the fluid passing through the injector causes the recirculated fluid to enter the path, and means for varying the percentage of the fluid recirculated.
